UNITED STATES PATENT OFFICE.

LARS HJORTH, OF CHICAGO, ILLINOIS, ASSIGNOR OF ONE-FOURTH TO
OSCAR STRAND, OF SOUTH CHICAGO, ILLINOIS.

COMBINED DISHING AND FLANGING MACHINE.

SPECIFICATION forming part of Letters Patent No. 766,826, dated August 9, 1904.

Application filed April 4, 1904. Serial No. 201,532. (No model.)

To all whom it may concern:

Be it known that I, LARS HJORTH, a citizen of the United States, residing at Chicago, in the county of Cook and State of Illinois, have 5 invented certain new and useful Improvements in a Combined Dishing and Flanging Machine, of which the following is a specification.

This invention relates to improvements in a machine to be used for dishing and flanging 10 by a rolling operation flat circular disks or plates such as are used for boiler-heads, tanks, and the like; and it consists in certain peculiarities of the construction, novel arrangement, combination, and operation of the various parts thereof, as will be hereinafter more 15 fully set forth and specifically claimed.

The principal object of the invention is to provide a machine of the above-named character which shall be strong, durable, and com- 20 paratively simple and inexpensive in construction and so made that its parts may be adjusted in such a manner as to readily admit of the insertion and the withdrawal of the plates or disks to be operated upon.

Another object of the invention is to pro- 25 vide a machine by means of which the disks may be dished by one operation and flanged by another or dished and flanged at the same time by a single operation.

A further object is to provide a flanging 30 and dishing machine the parts of which may be so adjusted that plates or disks of various dimensions can be treated by the same machine to produce flanged or unflanged heads 35 of the desired convexity and for boilers or tanks of different sizes.

Still another object of the invention is to provide means whereby in the operation of forming the flanges on the disks the same will 40 be strengthened at the bend thereof rather than weakened.

Other objects and advantages will be disclosed in the subjoined description and explanation.

In order to enable others skilled in the art 45 to which my invention pertains to make and use the same, I will now proceed to describe

it, referring to the accompanying drawings, in which—

Figure 1 is a side view in elevation of a com- 50 bined flanging and dishing machine embodying my invention, showing the parts in operative positions for dishing and flanging a disk and illustrating the disk in section. Fig. 2 is a front or face view thereof in elevation. 55 Fig. 3 is a central vertical sectional view of the machine, showing some of the parts in elevation. Fig. 4 is a view in elevation of the reversing mechanism for raising and lowering the driving-shaft of the machine, showing 60 a portion of the frame upon which it is mounted. Fig. 5 is a top or plan view of the machine, showing a disk in position to be operated upon, a part of the frame of the machine being broken away for the convenience of illustration. Fig. 6 is a plan view of the supporting-frame, showing the dishing and flanging mechanism removed and a part of said frame as being broken away for the convenience 65 of illustration. Fig. 7 is a view in side elevation of a portion of the dishing and flanging mechanism, showing certain parts in section and illustrating the disk or plate holding mechanism detached from the supporting-frame and also showing the disk held thereby 70 in a flat or horizontal position. Fig. 8 is a longitudinal sectional view of one of the seg- 75 mental gears used in the operation of dishing. Fig. 9 is a cross-sectional view thereof, taken on line 9 9 of Fig. 8. Fig. 10 is a central sec- 80 tional view of one of the dishing-rollers and its bearings. Fig. 11 is a plan view thereof, showing it removed from the arm of the seg- 85 mental gear. Fig. 12 is a detached view of the bearing-sleeve for one of the dishing-rollers. Fig. 13 is a plan view thereof. Fig. 14 is a detail view of a link used for connecting the bearings of said dishing-rollers. Fig. 15 is a detached end view of the frame which carries the flanging and driving mechanism, 90 with said mechanism removed. Fig. 16 is a plan view thereof. Fig. 17 is a longitudinal sectional view of said frame. Fig. 18 is a de- 95 tached view in elevation of an air-compressor

used for regulating the position of one of the wheels used in turning as well as flanging the disk. Fig. 19 is a similar view thereof looking in a different direction. Fig. 20 is a bottom view of a portion of the mechanism used for flanging the disk. Fig. 21 is a cross-section thereof, taken on line 21 21 of Fig. 20; and Fig. 22 is a side or face view of the roller-bearing bracket which said mechanism carries, showing the roller removed.

Like numerals of reference refer to corresponding parts throughout the different views of the drawings.

The base or foundation 30, upon which the machine rests, may be made of any suitable size, form, and material, but is herein shown as comprising a number of pillars 31, 32, 33, and 34, suitably spaced to support the different parts of the machine, as will be herein-after set forth. Horizontally mounted on the base 30 is a bed-plate 35, which is provided on its upper surface with a series of grooves 36 to receive projections or tongues 37 on the lower surface of a sliding plate 38, which, like the bed-plate 35, is substantially rectangular in shape and has at each of its rear corners an extension 39 to rest on the pillars 33 and 34 of the foundation and to support a portion of the frame of the dishing mechanism. The central rear portion of the sliding plate 38 is provided with a longitudinal recess 40 to permit of the movement of the support 41 for the front portion of the flanging-mechanism-carrying frame, which support is adjustably secured to the foundation by means of bolts 42 or otherwise. Each side of the bed-plate 35 is provided near its front end with a rack 43, with which engage pinions 44, mounted on the lower ends of shafts 45, which are vertically journaled on brackets 46, carried by the sliding plate 38, as is clearly shown in Figs. 1 and 2 of the drawings. Each of the shafts 45 is provided at its upper end with a hand-wheel 47, used for turning them, so that the sliding plate 38 may be reciprocated on the bed-plate. Mounted on the upper surface of the sliding plate 38 near each of its front corners is a standard 48, which has in its upper end a screw-threaded socket. Vertically located in each of the sockets of each of the standards 48 is a screw-threaded adjusting-rod 49, which is provided at its upper end with a hand-wheel 50, used for turning the same in raising and lowering or adjusting the upper frame, which carries a part of the dishing mechanism. This upper frame comprises side rails 51 and a front end rail 52, which are preferably made of channel-iron, as shown, and are united to form three sides of a rectangular figure, the rear portion being left open. As is clearly shown in Figs. 1 and 2, the adjusting-rods 49 are vertically journaled in or near the front corners of said frame. The rear ends of the rails 51 are downturned and pivotally secured on

the upper ends of standards 53, which extend upwardly a suitable distance and are supported on the extensions 39 of the sliding plate. Extending across the said upper frame and united to the said rails 51 thereof are beams 54, which are preferably in pairs and are located parallel with one another at a slight distance apart and near the middle of said frame.

Pivots secured at their inner ends to suitable brackets 55 on the front portion of the lower front cross-beam 54 near its middle are two segmental gears 56, which are radially arranged with respect to the center of the disk, as will be presently explained. The toothed end of each of the gears 56 extends to near the rear surface of the front rail 52, which carries downwardly-projecting curved guides 57, which are arranged in pairs, so that one of the segmental gears will operate between the members of one pair and the other gear between the members of the other pair, which serve to prevent lateral movement or displacement of the gears. Transversely journaled on the upper surface of the rail 52 is a shaft 58, on which are mounted two pinions 59 to mesh with the teeth of the segmental gears 56, and thereby raise and lower the same, which may be done by turning the shaft 58 by means of a hand-wheel 60, mounted thereon. As is clearly shown in Figs. 3, 5, and 8, each of the curved extensions or arms 61 of the gears 56, the inner end of which is pivoted, as before stated, to the lower front cross-beam 54, is provided with a longitudinal slot 62 for the reception and operation of the bearings and stems therefor of a series of rollers used in the operation of dishing the disk. The lower portion of each of the segmental gears is provided with a screw-threaded opening 63 to receive an adjusting-screw 64, each of which has on its end a hand-wheel 65 used for turning the same.

Located in each of the slots 62 of the arms 61 of the segmental gears are a number of sleeves 66, having portions 67, angular in cross-section, to rest in said slots. Each of the angular portions of each of the sleeves is provided on opposite sides with laterally-extending apertured lugs 68, and said sleeves are connected together by means of links 69, which have forked and apertured ends to receive the ends of the lugs 68 and suitable pivot-pins. Passing through an angular opening in each of the sleeves 66 is an angular stem 70, which has a roller 71 journaled on its lower portion. Located on the upper portion of the stem 70, so as to rest on the upper surface of the arm 61 of the segmental gear, is a cap 72, which is held in place by means of nuts 73, engaging screw-threads on the upper end of the roller-stem 70, as is clearly seen in Figs. 3, 7, and 10 of the drawings. The inner end of each of the screws 64 is connected to the sleeve 66 adjacent thereto by means of a swivel, so that by

turning the screw in the proper direction the series of rollers carried by each of the arms of the segmental gears will be moved back and forth, so that the proper adjustment there-
 5 of may be attained to give the desired convexity to the disk or plate 74 when the same is being dished. As before stated, the cross-beams 54 are located in pairs and a slight distance apart, as is clearly shown in Figs. 3
 10 and 5, and have located therebetween at about their middle a rectangular casing 75, which is held in place by means of flanged plates 76 and 77, bolted to said casing and the cross-beams. Fitted in the casing 75 is a shaft 78,
 15 on the lower portion of which is journaled a beveled gear 79, which is preferably made of two pieces secured together by means of bolts 80, which is best shown in Fig. 1 of the drawings. The lower end of the shaft 78 is provided with a socket 81, in which is fitted a stub-shaft 82 on the upper surface of a revolving disk 83, which has interposed between it and the lower surface of the shaft 78 a series of antifriction-balls 84 to provide a ball-bearing in said disk. This disk is rotatably secured on the shaft 78 by means of semi-circular pieces 85, which surround the lower portion of the shaft and engage a groove in the upper portion of the disk and are held
 20 together by means of bolts 86 passing through lugs 87 on the meeting ends of said pieces. Extending diagonally from near the rear end of each of the side rails 51 of the upper frame for the dishing mechanism is a beam 88, which
 25 has its inner end connected to one of the rear cross-beams 54 and carries on its outer portion an arm 89, in each of which arms is horizontally journaled a screw-threaded shaft or worm 90. Horizontally journaled on and
 30 about the middle of the front rail 52 is a screw-threaded shaft or worm 91, which, as well as the shafts 90, has on its outer end a hand-wheel 92 for turning the same. By reference to Figs. 1, 3, and 5 of the drawings it
 35 will be seen that the shafts 90 and 91 are radially arranged with respect to the beveled gear 79 and that each of said shafts carries on its inner end a beveled pinion 93 to mesh with said gear. Loosely mounted on the screw-
 40 threaded portions of each of the shafts 90 and 91 is a downwardly-projecting detent or foot 94, the openings in which to receive the shafts are screw-threaded, so that when the shafts are turned said detents will travel back and
 45 forth thereon.

Vertically mounted on the upper surface of the sliding plate 38 and radiating from a central point near the inner end of the recess 40 in said plate are a series of braces 95, which
 50 are arranged in pairs, as is clearly shown in Fig. 6 of the drawings, and have their upper edges curved. Each of these brace-plates is provided with two or more series of openings 96 and 97, the former of which are vertically

arranged, and the latter are arranged in inclined rows, as is clearly shown in Figs. 1 and 3 of the drawings, and said openings are for the reception of bolts 98, which pass through openings in the shanks 99 of hangers 100, on each of which is journaled a roller 101 to support the lower surface of the disk or plate 74 and to coöperate with the rollers 71 in the operation of dishing the disk. By arranging the openings 96 in the brace-plates 95 vertically and the openings 97 therein in inclined rows it is apparent that the shanks 99 of the brackets or hangers 100 for the rollers 101 may be adjusted so as to give the proper convexity to the disk 74 when it is being dished. Mounted on the upper surface 80 of the brace-plates 95 at their adjacent ends is a table 102, which has on its lower surface a series of downwardly-extending lugs 103, which project between the inner ends of the plates 95 and are bolted thereto. This table 85 has in its upper surface an annular groove 104, in which are radially journaled a series of rollers 105, which are movably located in said groove, so that when it is desired to flange the disk 74 without dishing it rollers 90 with a horizontal surface may be substituted for the rollers 105, which have inclined surfaces, as shown in Figs. 3 and 6, to permit of the disk being properly dished. The upper surface of the table 102 is provided with a 95 central socket 106, in which is journaled the stub-shaft 107 of a rotatable disk or plate 108, between the lower surface of which and the table 12 are interposed antifriction-balls 109 to furnish ball-bearings therefor. The disk 100 108 serves to rotatably support the disk or plate 74 at its center, and is clamped or pressed on its upper surface at said point by the rotatable disk 83, as is clearly shown in Figs. 1, 2, 3, and 7 of the drawings.

The frame for the flange and driving mechanism comprises a base 110, from the front end of which extends forwardly-projecting arms 111, which are pivotally secured to the upper end of the standard 41, which, as before stated, is adjustably mounted on the foundation, so that it can be moved back and forth thereon within the recesses 40 of the sliding and bed plates. Each of the arms 111 is provided with an opening 112, in each of which is located the shank 113 of a bracket 114, on which is journaled a roller 115, said rollers being employed to support the disk or plate 74 in the operation of dishing or flanging the same. Extending upwardly from the front portion of the base 110 are transverse uprights 116, each of which is provided with a groove 117 on its inner face for the reception and operation of a yoke 118, which is mounted on the upper end of the piston 119 of an air-compressor 120, which may be of the ordinary or any preferred construction and is located on the base 110 between the uprights 116, as is

clearly shown in Fig. 3 of the drawings. Journaled on the yoke 118, so as to extend longitudinally with the frame, is a shaft 121, on the front end of which is detachably mounted 5 a beveled wheel 122, which may be removed and replaced by another wheel having a greater or less degree of bevel, as may be required to give the proper angle to the flange 123 being formed on the plate or disk. On 10 the rear end of the shaft 121 is mounted a gear 124, which normally meshes with a gear 125 on the main or driving shaft 126, which is longitudinally journaled on the upper portion of the frame and has mounted on its front 15 end a wheel 127, which impinges the upper surface of the disk or plate 74, which will be caused to rotate by means of the revolution of the wheels 122 and 127, as is apparent. The shaft 121 may be raised and lowered by 20 means of the compressor 120, so that the disk 74 may be inserted between the wheels 122 and 127 or so that the pressure of the former wheel may be regulated so as to clamp the disk between it and the wheel 27 sufficiently 25 to cause it to rotate by reason of the frictional contact of said wheels. Mounted on the rear portion of the driving-shaft 126 is a gear 128, which meshes with a gear 129, mounted on a shaft 130, journaled on the rear portion 30 of the frame, and which may be driven by means of an electric motor (not shown) mounted on the rear end of the frame for the flanging and driving mechanism or by any other suitable means, so as to transmit power 35 to the driving-shaft. Mounted on the shaft 126, between the gears 125 and 128, is a gear 131, which meshes with a pinion 132, mounted on a shaft 133, which is journaled longitudinally with the shaft 126 and below the same. 40 On the front end of the shaft 133 is mounted a beveled gear 134, which meshes with a smaller gear 135, mounted on the upper end of a shaft 136, vertically journaled below the shaft 133. On the lower end of the shaft 136 45 is a beveled gear 137, which meshes with beveled gears 138 and 139, mounted on a shaft 140, transversely journaled on the lower portion of the frame. Each of the gears 138 and 139 is provided on its inner surface with a 50 clutch-face 141 to coact with a clutch 142, which is movably mounted on the shaft 140, the position of which clutch may be shifted by means of a lever 143, suitably fulcrumed on the frame. The inner end of this lever is 55 formed with a yoke 144 and is connected to the clutch in the ordinary manner. On each end of the shaft 140 is mounted a gear 145, which meshes with the vertically-curved rack-bars 146, one of which is suitably mounted on 60 the foundation on each side of the frame 110, as is clearly shown in Fig. 5 of the drawings. By moving the lever 143 in the proper direction it is evident that the clutch 142 will be thrown into engagement with one of the gears 138 or 139, so as to cause the shaft 140 to be 65 rotated in the proper direction to raise or lower the frame which carries the flanging and driving mechanism. Transversely journaled in suitable bearings 147 on the front part of the frame 110 and below the driving-shaft 70 is a rock-shaft 148, on which is rigidly mounted a bracket 149, on which is transversely journaled in a suitable recess 150 a roller 151, used for forming the flange on the disk or plate. On each end of the shaft 148 75 is mounted a segmental gear 152, which meshes with similar gears 153, rigidly mounted on another rock-shaft, 154, which has its bearings 155 in the sides of the frame. The shaft 154 is provided at one of its ends with a hand-wheel 155, used for turning the same so as to adjust the roller 151 to the proper position to form the flange 123 on the disk or plate, which is done by reason of the engagement of the racks 152 and 153, as will be clearly understood by reference to the various views of the drawings. 80

The operation of the machine is as follows: When it is desired to dish or flange a disk or plate, the upper frame may be raised sufficiently to permit of the plate being inserted between the disks 83 and 108 by turning the adjusting-shafts 49 in the proper direction, or if it is desired to raise the upper frame higher than the shafts 49 will force it said frame 95 may be raised by means of suitable tackle. After the plate or disk shall have been inserted between the rotatable disks 83 and 108, so as to rest on the latter, the upper frame may 100 be lowered, when by turning the frame or screw-shafts 90 and 91 the detents or feet carried thereby will be caused to travel on said rods, so as to center the disk or plate, after which the upper frame may be screwed down farther, so as to cause the disk or plate to be 105 firmly clamped between the rotatable disks at the center of the machine. In order to dish the plate or disk, the brackets or hangers 100, carrying the rollers 101, may be adjusted to the proper inclination by means of the opening in the brace-plates 95 and bolts located 110 therein, when by turning the shaft 58 the segmental gears 56 will be forced downwardly, thus causing the rollers 71, which are carried by said gears and which may be suitably adjusted by means of the adjusting screws or rods 64, so that said rollers will impinge the upper surface of the plate or disk, which in its heated condition will be bent downwardly, 115 onto the rollers 101, in which position it will be rotated between the rollers 71 and 101 by reason of the frictional contact of the wheels 122 and 127, which are driven as above set forth. If it is desired to form the disk or plate 74 with a flange, the rock-shaft 154 may be turned 120 in the proper direction to cause the gears 153 thereon to force the gears 152 on the shaft 148 in the proper direction to cause the roller 151 125

to impinge the upper surface of the edge of the disk or plate, thus forcing it downwardly over the periphery of the beveled wheel 122, in which operation the disk or plate will be 5 upset or slightly reinforced at the bend of the flange, thus strengthening the same at the said point. In the operation of flanging or dishing that portion of the disk near the driving-wheels 122 and 127 will be supported by means 10 of the rollers 115, which are carried by the frame for the flanging and driving mechanism.

Having thus fully described my invention, what I claim as new, and desire to secure by Letters Patent, is—

15 1. In a dishing-machine, the combination with means for rotatably supporting the lower surface of the disk, whereby it may be concaved downwardly, of an upper frame adjustable vertically and horizontally located above 20 said supporting means, and means carried by said frame to impinge the upper surface of the disk at its center and to press it downwardly, substantially as described.

2. In a dishing-machine, the combination 25 with rotatable means for supporting the lower surface of the disk so that it can be concaved downwardly, of an upper frame adjustable vertically and horizontally located above said supporting means, adjustable means carried 30 by said frame to impinge the upper surface of said disk at its central portion, and means to rotate the disk, substantially as described.

3. In a dishing-machine, the combination 35 with a rotatable support for the lower surface of the disk, of an upper frame adjustable vertically and horizontally located above the said support, means carried by said frame to impinge the upper surface of the disk at its central portion and to press it against said support, 40 rollers adjustably mounted on the support, and means to rotate the disk, substantially as described.

4. In a dishing-machine, the combination 45 with a rotatable support for the disk, of a series of rollers adjustably mounted and radially arranged to impinge the lower surface of the disk, an upper frame adjustable vertically and located horizontally above said support, means carried by said frame to center the disk 50 on and to press it against said support, and a series of rollers adjustably mounted on the upper frame to impinge the upper surface of the disk, substantially as described.

5. In a dishing-machine, the combination 55 with a rotatable support for the disk, of a series of rollers radially arranged and adjustably mounted to impinge the lower surface of the disk, an upper frame adjustable vertically and located horizontally above the said support, means carried by said frame to press the disk against the rotary support therefor, and a series of rollers adjustably mounted on the upper frame, substantially as described.

6. In a dishing-machine, the combination

with a supporting-frame for the disk, of a rotary disk mounted on the central portion of said frame, a series of rollers radially and adjustably mounted on said frame, an upper frame pivotally supported at one of its ends and vertically adjustable at its other end, a shaft vertically mounted on the upper frame, a disk rotatably journaled on the lower end of said shaft, and a series of rollers adjustably mounted on the upper frame, substantially as described.

75

7. In a dishing-machine, the combination with a supporting-frame for the disk, of a table mounted on the upper central portion thereof and having in its upper surface an annular groove, a disk rotatably mounted on the table, 80 a series of rollers radially and adjustably mounted on said frame an upper frame adjustable vertically and horizontally located above the supporting-frame, and means carried by the upper frame to impinge the upper 85 surface of the disk and to press it against the supporting-disk, substantially as described.

8. In a dishing-machine, the combination with a supporting-frame for the disk, of a table mounted on the upper central portion thereof 90 and having in its upper surface an annular groove, a disk rotatably mounted on the table, a series of rollers radially journaled on the table so as to operate in said groove, a series of rollers radially and adjustably mounted on 95 said frame, an upper frame adjustable vertically and horizontally located above the supporting-frame, and means carried by the upper frame to impinge the upper surface of the disk and to press it against the supporting- 100 disk, substantially as described.

9. In a dishing-machine, the combination with a supporting-frame for the disk, of a table mounted on the upper central portion thereof 105 and having in its upper surface an annular groove, a disk rotatably mounted on the table, a series of rollers radially journaled on the table and operating in said groove, a series of rollers radially and adjustably mounted on said frame, an upper frame adjustable vertically and horizontally located above the supporting-frame, means carried by the upper frame to center the disk on and to press it against the rotatable disk, and a series of rollers adjustably mounted on the upper frame 115 to impinge the upper surface of the disk, substantially as described.

10. In a dishing-machine, the combination with a supporting-frame for the disk, of a rotary disk mounted on the central portion of 120 said frame, a series of rollers radially and adjustably mounted on said frame, an upper frame adjustable vertically and horizontally located above the supporting-frame, a shaft vertically mounted on the upper frame, a disk rotatably journaled on the lower end of said shaft, a beveled gear on said shaft above the disk, a number of screw-rods horizontally and

radially journaled on the upper frame each having at its outer end means to turn the same, a beveled gear on the inner end of each of said rods to mesh with the first-named gear, 5 and a detent loosely mounted on each of said rods, substantially as described.

11. In a dishing-machine, the combination with a supporting-frame for the disk, a rotary disk mounted on the upper central portion of 10 said frame, a series of rollers radially and adjustably mounted on said frame, an upper frame pivotally supported at one of its ends and vertically adjustable at its other end, a shaft vertically mounted on the upper frame, 15 a disk rotatably journaled on the lower end of said shaft, a beveled gear journaled on said shaft above the disk, a number of screw-rods horizontally and radially journaled on the upper frame, each having at its outer end means 20 to turn the same, a beveled gear on the inner end of each of said rods to mesh with the first-named beveled gear, a detent loosely mounted on each of said rods, and means carried by said frame to impinge the upper surface of 25 the disk, substantially as described.

12. In a dishing-machine, the combination with means for rotatably supporting the lower surface of the disk, whereby it may be concaved downwardly, of an upper frame adjustable vertically and horizontally located above 30 said supporting means, a plurality of segmental gears radially arranged on the upper frame with respect to the center of the disk and pivotally secured on said frame at their 35 inner ends, a number of rollers adjustably secured on each of the segmental gears, a shaft horizontally journaled on the upper frame near the outer ends of said gears, pinions on said shaft to mesh with said gears and means 40 to turn said shaft, substantially as described.

13. In a dishing and flanging machine, the combination with means for rotatably supporting the disk, of an upper frame adjustable vertically and horizontally located above the 45 said supporting means, means carried by the upper frame to press the disk against said support, a frame for the flanging and driving mechanism pivotally supported at its front end, a driving-shaft longitudinally journaled 50 on said frame, a wheel on the front end of said shaft to impinge the upper surface of the disk, a shaft movably journaled below the driving-shaft and geared thereto, a wheel on the front end of the movable shaft to impinge 55 the lower surface of the disk, means to raise and lower the rear end of the frame for the flanging and driving mechanism, a rock-shaft transversely journaled on said frame near the edge of the disk, a roller rigidly mounted 60 transversely on the rock-shaft, means to rock said shaft, and means to raise and lower the movable shaft, substantially as described.

14. In a flanging-machine, the combination with means for rotatably supporting the disk,

of a frame for the flanging and driving mechanism pivotally supported at its front end near the center of the disk, a driving-shaft longitudinally journaled on said frame, a wheel on the front end of said shaft to impinge the upper surface of the disk, a shaft 65 movably journaled below the driving-shaft and geared thereto, a wheel on the front end of the movable shaft to impinge the lower surface of the disk, means to raise and lower the rear end of the frame, a rock-shaft transversely journaled on said frame near the said 70 wheels, a roller rigidly mounted transversely on the rock-shaft, means to rock said shaft, and means to raise and lower the movable shaft, substantially as described. 75

15. In a flanging-machine, the combination with means for rotatably supporting the disk, of a frame for the flanging and driving mechanism pivotally supported at its front end near the center of the disk, a driving-shaft 80 longitudinally journaled on said frame, a wheel on the front end of said shaft to impinge the upper surface of the disk, a shaft movably journaled below the driving-shaft and geared thereto, a wheel on the front end of the movable shaft to impinge the lower surface of the disk, means to raise and lower the rear end of the frame, a rock-shaft transversely journaled on said frame near the said 85 wheels, a roller transversely and rigidly mounted on said rock-shaft, a gear on the rock-shaft, another rock-shaft transversely journaled near the first-named one, and having means to turn the same, a gear on the last-named rock-shaft meshing with the gear 90 on the first-named rock-shaft, and means to raise and lower the movable shaft, substantially as described. 95

16. In a dishing and flanging machine, the combination with a rotatable support for the disk, of an upper frame adjustable vertically and horizontally located above said supporting means, means carried by said frame to center the disk on and to press it against said support, a frame for the flanging and driving mechanism pivotally supported at its front end, a driving-shaft longitudinally journaled on said frame, a gripping-wheel on the front end of said shaft to impinge the upper surface of the disk, a shaft movably journaled 105 below the driving-shaft and geared thereto, a grip-wheel on the front end of the movable shaft to impinge the lower surface of the disk, a rock-shaft transversely journaled on said frame near the grip-wheels, a roller transversely and rigidly mounted on the rock-shaft, means to rock said shaft, and means to raise and lower the movable shaft, substantially as 110 described. 115

17. The combination with a fixed bed-plate 120 having toothed racks on its sides, of a plate movably mounted thereon, gears journaled on the movable plate to engage said rack, a sup- 125

porting-frame comprising a series of brace-
plates radially mounted on the movable plate,
a rotary disk mounted on the upper central
portion of the brace-plates, a series of rollers
5 radially and adjustably mounted on said plates,
an upper frame pivotally supported at one of
its ends on the movable plate and vertically
adjustable at its other end, means carried by

the upper frame to impinge the upper sur-
face of the disk being operated on, substan-
tially as described.

LARS HJORTH.
